(57) **CLAIM**

The ornamental design for a ceiling panel as shown and described.

DESCRIPTION

FIG. 1 is a bottom perspective view of one embodiment of a ceiling panel according to an aspect of the present subject matter.

FIG. 2 is a front view of the ceiling panel illustrated in FIG. 1.

FIG. 3 is a side view of the ceiling panel illustrated in FIG. 1.

FIG. 4 is a top view of the ceiling panel illustrated in FIG. 1.

FIG. 5 is a bottom view of the ceiling panel illustrated in FIG. 1.

FIG. 6 is a top perspective view of the ceiling panel illustrated in FIG. 1, particularly illustrating the ceiling panel assembled relative to a plurality of similarly configured ceiling panels in a ceiling panel arrangement.

FIG. 7 is another bottom perspective view of the ceiling panel illustrated in FIG. 1, particularly illustrating the ceiling panel assembled relative to a plurality of similarly configured ceiling panels in a ceiling panel arrangement.

FIG. 8 is a bottom perspective view of one embodiment of a ceiling panel according to an aspect of the present subject matter.

FIG. 9 is a front view of the ceiling panel illustrated in FIG. 8.

FIG. 10 is a side view of the ceiling panel illustrated in FIG. 8.

FIG. 11 is a top view of the ceiling panel illustrated in FIG. 8.

FIG. 12 is a bottom view of the ceiling panel illustrated in FIG. 8.

FIG. 13 is a top perspective view of the ceiling panel illustrated in FIG. 8, particularly illustrating the ceiling panel assembled relative to a plurality of similarly configured ceiling panels in a ceiling panel arrangement.

(Continued)

panel assembled relative to a plurality of similarly configured ceiling panels in a ceiling panel arrangement.

FIG. 14 is another bottom perspective view of the ceiling panel illustrated in FIG. 8, particularly illustrating the ceiling panel assembled relative to a plurality of similarly configured ceiling panels in a ceiling panel arrangement.

FIG. 15 is a bottom perspective view of one embodiment of a ceiling panel according to an aspect of the present subject matter.

FIG. 16 is a front view of the ceiling panel illustrated in FIG. 15.

FIG. 17 is a side view of the ceiling panel illustrated in FIG. 15.

FIG. 18 is a top view of the ceiling panel illustrated in FIG. 15.

FIG. 19 is a bottom view of the ceiling panel illustrated in FIG. 15.

FIG. 20 is a top perspective view of the ceiling panel illustrated in FIG. 15, particularly illustrating the ceiling panel assembled relative to a plurality of similarly configured ceiling panels in a ceiling panel arrangement; and,

FIG. 21 is another bottom perspective view of the ceiling panel illustrated in FIG. 15, particularly illustrating the ceiling panel assembled relative to a plurality of similarly configured ceiling panels in a ceiling panel arrangement.

The dashed or broken lines, including any surface lines, contained within the figures represent portions of the disclosed ceiling panel that form no part of the claimed design.
